PUMP AND MOTOR

Hans Joseph Zimmermann, Elkins Park, Pa.

Application September 20, 1938, Serial No. 230,854
In Great Britain September 22, 1937

4 Claims. (Cl. 103—162)

This invention relates to pumps of the kind in which pistons or plungers are reciprocated by means of swash plates, and it comprehends certain improvements therein having for their object a pump which is of compact formation in relation to capacity or duty; which will satisfactorily deliver liquids or gases at high pressures; which will function reliably over long periods; and, therefore, is well adapted for supplying oil under pressure to the several parts of aircraft; which can, if desired, be self-adjusting for regulation of delivery volume against constant pressure, or, alternatively, may be regulated manually; and which is adaptable to hydraulic gears.

Having the aforesaid and other objects in view, as will appear in the following specification, the invention consists in a pump or motor, the characteristic feature of which is the employment of a plurality of swash plates spaced apart, and a plurality of plungers intermediate the swash plates.

Various arrangements of swash plates, plungers, and driving mechanism, can be made according to the effects desired; and in a preferred arrangement, two swash plates are incorporated in such a manner that they are maintained in parallelism.

A pump has been suggested having two spaced swash plates and two independent sets of cylinders and pistons, separately operated and controlled, arranged between the plates, each alternate cylinder being arranged for its piston to work in opposite directions.

Various arrangements of swash plates have been proposed, and the invention is concerned more particularly with pumps or motors of the kind in which two swash plates are spaced some distance apart and the plungers are arranged intermediate to the two plates in such a manner that one end of each plunger is operated by thrust from one plate and the other end by thrust from the other plate, providing positive actuation on both out and return strokes. Such constructions involve stepped or two diameter plungers and annular working chambers.

In the kind of pump or motor with which this invention is more particularly concerned, the invention consists in arranging the plungers in two co-operating groups with one group in opposite reciprocal phase to the other group to balance the axial forces within the system. In a preferred form, the individual plungers of one group are in alternate relation to the individual plungers of the other group. Such arrangement is applicable to pumps or motors of the fixed

swash plate type or to those in which the angle of inclination of the plates is concurrently adjustable to vary the delivery volume.

The invention further consists in provision for self-adjustment of the angle of the swash plates by a device exposed to the pressure of the delivery side in order to maintain constant pressure in a communicating receiver or system.

The invention further consists in provision as aforesaid which includes a plunger having one end exposed to the delivery side, means of connection between the other end of the plunger and the swash plate or plates, and a resistance opposing the actuating movement of the plunger, said resistance being adjustable to enable the delivery pressure to be varied.

In order that this invention may be clearly understood and readily carried into practice, reference may be had to the accompanying drawing.

Fig. I is a longitudinal section of a pump embodying the present improvements.

Fig. II is a staggered cross-section of the same, taken approximately as indicated by the plane II—II in Fig. I; and,

Fig. III is a fragmentary view of means for adjusting the resistance of the spring included in Fig. I.

Each swash plate may include two sections separated by ball or other anti-friction bearings; one indicated by 1 is the non-rotative section 30 journaled at 2 in the housing 3; the other 4 for contact with the ends of the plungers 22, 23. A suitable form for the sections 1 is that of a segment of a hollow spheroid with two integral trunnions 2 about the axis of which the swash plate may be adjusted for varying its inclination.

The driving shaft 6 serves two functions; firstly, it carries the work chambers 7 in an orbital path around the axis of rotation, and secondly it acts as the moving element of a port system for controlling the suction and delivery ports. With these functions in view, a number of two-diameter bores are provided in an enlargement 8 of, or part surrounding, the shaft 6, for co-operation with passages leading inwards to the shaft bore, as will be later described. The plungers 22, 23, like the bores in which they slide, are of two diameters with the smaller parts 11 of said plungers acting as push rods, and the larger diameter parts acting as working pistons, 50 with the ends of said plungers preferably rounded for rubbing contact with the swash plate sections 4 to accommodate the slight relative movement due to the angularity of the swash plates 1 when adjusted from the neutral position.

The plungers 22, 23 are moved positively in both directions of reciprocation, since at one end they contact with one swash plate and at the other end they contact with the other swash plate, hence it will be apparent that springs are not needed for effecting the suction stroke of said plungers. Any other appropriate arrangement of passages and ports may be used for controlling the flow of liquid or gas into or from the annular working chambers 7.

According to the duty to which the improved pumps are to be put, the working stroke of the plungers 22, 23 may be fixed or variable. When the stroke is variable, the means for varying the inclination of the swash plates 1 may be movable by an operator, or it may be self-acting. Where the pump is required to deliver into, say a vessel or part in which constant pressure is to be maintained, the self-acting control pressure may be originated by exposing one end of a plunger 16 to the fluid in the delivery side of the pump.

An example of such control mechanism, as depicted in Figs. I and II, comprises an auxiliary plunger 16 having one end open to the delivery port 28, and the other end in contact with a projection 18 from the non-rotatable or spheroid part of one of the swash plates 1, to move said plates about their trunnions 2 against the resistance of a spring 19. Conveniently, this spring 19 of the coiled compression type is housed in the groove of a boss 20 on the other side of the casting 3, with one end of said spring abutting against a projection 21 on the trunnion-mounted part of the adjoining swash plate 1, and the other end against the boss end 20. If desired, the latter end may be rendered adjustable from the exterior by the use of a shouldered screw in the end of the boss 20, Fig. III, to vary the compression effect of the spring 19 and consequently the delivery pressure to be varied. When the pressure in the delivery port 28 rises above the predetermined level, the control plunger 16 is displaced against the resistance of the spring 19 and movement communicated to the swash plates 1 which are turned on their trunnions 2 to reduce the angle of inclination, the turning movement continuing until the balance of pressure is restored, if necessary to the neutral point where reciprocative motion of the plungers 22, 23 ceases. A reverse action takes place when the pressure in the delivery port 28 falls. In some applications, it may be useful to carry the swash plates 1 beyond the neutral position, the discharge then functioning as the suction, and the suction becoming the delivery.

The two swash plates 1 being maintained in parallelism, the plungers 22, 23 are disposed in two groups so that one group is in opposite reciprocative phase to the other group, whereby the axial forces are balanced within the rotative system. Preferably, also, the units of one group are disposed in alternate relation to the units of the other group as best understood from Fig. III. Diametrically opposite plungers 22 and 23 are disposed in an axial sense, in opposition so that the push rod smaller part 11 of one plunger and the larger diameter part of the other plunger 22 or 23 are in contact with the same swash plate 1, the suction strokes are concurrent, and the delivery strokes are concurrent. Seen from the end of the driving shaft as in Fig. II, the small and large ends of the plungers 22, 23 appear in alternate relation, each end of the smaller part 11 being intermediate a pair of large ends, and as a corollary, each large end is intermediate two small

ends, the terms large and small having reference to the different diameters.

The distribution of pressure between two swash plates 1 and any two diametrically-opposite plungers 22, 23 is such that the forces are balanced and the four elements can be regarded as a closed structure. The end pressure of the fluid on the working chamber 7 is similarly balanced, as the two plungers 22, 23 are moving in opposite directions at the same time; thus the rotor is balanced for pressure as well as dynamically. Adjacent plungers 22, 23 move rectilinearly in a common direction, except when passing the neutral points where reversal occurs, and thus when one is delivering, the next adjacent one is executing its suction stroke.

An arrangement of passages and ports utilizing a central fixed stub shaft 24 for controlling the flow of fluid, is included in Figs. I and II, wherein in the enlargement 8 of the driving shaft 6 has a blind bore 21 supported rotatively on the fixed stub shaft 24. The shaft 24 has two parallel holes 25, 26 communicating at the anchored end of said shaft by transverse ducts with registering passages 27, 28 in the housing 3, one passage 27 for suction and the other 28 for delivery. At two spaced positions intermediate the ends of the shaft 24 are transverse passages 29, 30 connecting the holes 25, 26 with the outer surface of said shaft, which at such places is cut away to a cross-section resembling that of an ellipse, as seen in Fig. II, for maintaining communication between the working chambers 7 and the respective holes 25, 26 in the shaft 24 during the suction and delivery strokes respectively. Radial passages 31 lead from the working chambers 7 to the bore 21 of the shaft enlargement 8, thus forming a means of communication while traversing the cut-away portions 29, 30 of the fixed shaft 24, but being shut off while moving over the full-diameter segments of said shaft.

The apparatus described is suitable for use as a pump, a compressor, or as a motor by supplying it with fluid under pressure. When constructed for operator control of the swash plates 1, the pump shown can be run in either direction of rotation since the port control arrangements are symmetrical about the central longitudinal plane of the pump.

Having thus described my invention, I claim:

1. A pump or motor of the type described having two spaced swash plates, two-diameter plungers intermediate the swash plates, said plungers being arranged in two co-operating groups with one group in opposite reciprocative phase to the other group, thereby to balance the axial forces.

2. A pump or motor of the kind described having two spaced swash plates and plungers or pistons intermediate the plates, which includes a cylinder member intermediate the plates, and two groups of plungers or pistons slidably mounted in said member, said plungers being arranged with one group in opposite reciprocative phase to the other group, and disposed so that the plungers of one group are in alternate relation to those of the other group.

3. In a pump or motor of the type described including a casing with suction and delivery passages, the combination of two spaced swash plates, two-diameter plungers intermediate the swash plates, said plungers arranged in two co-operating groups with one group in opposite reciprocative phase to the other group, an auxiliary plunger with one end exposed to the pres-

sure in the delivery passage, an abutment on one of the swash plates engaging the other end of said plunger, and a resistance means sustained intermediate an abutment on the other swash plate and an offset from the casing wall for varying the working stroke of plungers aforesaid.

4. The combination of claim 3, wherein the casing wall offset is in the form of a grooved boss,

and an adjustable shouldered screw projects into the end of the boss groove, remote from the adjoining swash plate abutment, supports the adjoining end of the resistance means, whereby the inclination of the swash plates is controlled by variations in the delivery pressure of the pump or motor.

HANS JOSEPH ZIMMERMANN.
